[57] CLAIM

The ornamental design for a pacifier shield, as shown and described.

DESCRIPTION

FIG. 1 is a front elevational view of a pacifier shield, showing our new design;

FIG. 2 is a top plan view thereof, the bottom plan view being a mirror image thereto;

FIG. 3 is a rear elevational view thereof;

FIG. 4 is a right side elevational view thereof, the left side elevational view being a mirror image thereto;

FIG. 5 is an enlarged cross-sectional view thereof, taken along line 5—5 of FIG. 3; and,

FIG. 6 is a perspective view thereof.

FIG. 2

FIG. 6

FIG. 1

FIG. 4
